William H. Macdonald, Passaic, N. J.

Application February 7, 1933, Serial No. 655,569

44 Claims. (Cl. 101—93)

This invention relates to ticket-printing machines, and more particularly to a printing machine having provision for the mechanical setting and restoring of type.

5 The invention is particularly applicable to a machine for printing series of tickets or the like, in which one or more of the characters requires frequent changing and provides for making the necessary type changes without materially delaying the printing operations.

An object of the invention is to provide a simplified type-setting mechanism in a machine of the character specified.

15 Another object is to provide for the rapid restoring and resetting of the type.

A further object is to provide for selectively resetting one or more of the type characters without disturbing the setting of the other characters.

20 A still further object is to provide a simple, convenient and dependable device of the type above indicated.

In one embodiment of the invention, the type-setting machine comprises a pair of aligned stacks of grooved type carriers, one stack comprising a type-storage magazine and the other stack comprising a type-receiving magazine and printing form. The type pieces are placed end-to-end in the storage magazine in rows which are adapted to slide into the type-receiving magazine. Means is provided for sliding the various rows selected distances into the type-receiving magazine and for locking the type in position for printing. The longitudinal position of the rows of type with respect to the magazines determines the particular type face which is brought into printing position. The type-receiving magazine serves as a printing form and is adapted to cooperate with suitable inking means and to be brought into printing relationship with the paper-supporting bed. After the printing operation, the type-receiving magazine is again brought into alignment with the type-storage magazine, whereupon the type may be restored or reset as desired.

Although the various novel features which are believed to be characteristic of this invention will be particularly pointed out in the claims 50 appended hereto, the invention itself, as to its objects and advantages and the manner in which it may be carried out, may be better understood by referring to the following description taken in connection with the accompanying drawings forming a part thereof, in the various

figures of which like reference characters have been used to designate like parts.

In the drawings:

Figure 1 is a perspective view of a printing machine embodying the present invention; 60

Figure 2 is a plan view of a ticket printed on the machine of Figure 1;

Figure 3 is a side elevation of the machine shown in Figure 1;

Figure 4 is a partial top plan view thereof; 65

Figure 5 is a side elevation of the type magazines and supporting frame;

Figure 6 is a plan view of the type magazines and frame;

Figure 7 is a section taken on the line 7—7 of 70 Figure 6;

Figure 8 is a longitudinal section of the type magazines in type-setting position;

Figure 9 is a section taken on the line 9—9 of Figure 8 showing the arrangement of the type- 75 printing faces;

Figure 10 is a longitudinal section of the type magazines in printing position;

Figure 11 is a section taken on the line 11—11 of Figure 10; 80

Figure 12 is a detail view of the guide bars;

Figure 13 is a section taken on the line 13—13 of Figure 12;

Figure 14 is a partial plan view of a modified form of index plate and operating levers; 85

Figure 15 is a section taken on the line 15—15 of Figure 14;

Figure 16 is a perspective of the aligning bar, showing the cam surface for aligning the type magazines; and 90

Figure 17 is a section taken on the line 17—17 of Figure 3, showing the bar supports.

In the following description and in the claims, various parts are referred to by specific names for convenience, but they are intended to be 95 interpreted as broadly as the state of the art will permit.

In the embodiment of the invention illustrated in the drawings, the ticket-printing machine is shown as comprising a main frame or stand 100 having uprights 20 and side members 21, 22 and 23, which are joined thereto in any suitable manner and form supports for parts of the apparatus to be described. Cross members 24 are carried by side members 23 and carry printing 105 head supports 25, which may be secured thereto by bolts 26 and spacing members 30 (Figures 1 and 3). The printing head supports 25 carry type magazine supports 31 and a printing bed or paper support 32 (Figure 5). The paper 110

support 32 may comprise a pair of side members 33 (Figure 8) which are pivoted to the supports 25 by bolts 34 extending through elongated arcuate slots 35, which are formed in said side members 33. The side members 33 bear against adjusting screws 36, which are threaded in blocks 40 mounted on said printing head supports 25. The side members 33 also carry a bed plate 41, which is adapted to receive the 10 paper or the like to be printed, and a stop member 42 which is adapted to control the position of the paper during printing.

The type magazine supports 31 carry a pair of type magazines 43 and 44 (Figures 5-7), 15 which are adapted to constitute the type-storage magazine and the type-receiving magazine respectively. The type-storage magazine 43 comprises a stack of slotted type carriers 45, each of which comprises a channel plate 46 having 20 type-spacing means 50 secured thereto or integrally formed therewith and carrying a cover plate 51, which is secured thereto by screws 52. The spacing means 50 form a plurality of channels adapted to receive rows of type 53, 25 which are placed end-to-end in the various channels, as illustrated in Figures 8 and 10, with the printing face of each of the type pieces abutting against the base of the next type piece.

The various type carriers are mounted on 30 brackets 54, which are supported on cross members 55 secured to magazine supports 31.

The position of the rows of type in the various channels is controlled by pushers 56 (Figures 8 and 10), which are mounted on flexible 35 wires 60 adapted to slide in flexible cables or sheaths 61. Said pushers 56 are adapted to slide in the various channels and to hold the rows of type in various selected positions. One end of each of the flexible cables 61 is secured 40 in a yoke 62 (Figure 6) as by set screws 63. The other end of certain of the flexible cables may be secured by set screws 64 to a cross bar 65 (Figures 1, 3 and 17), which may, for example, be supported on a cross member 66 carried by 45 side members 21 of the main frame. Certain others of the flexible cables may be secured in guide bars 70 (Figures 1, 12 and 13), which are pivotally mounted on a rod 71 and spaced by spacing means 72. The rod 71 may be secured to the side members 21 as by yokes 73. The guide bars 70 are formed with longitudinal 50 grooves 74 to receive the flexible wires 60 and are arcuate in longitudinal section for the purpose to be described. The free ends of the guide bars 70 may rest on a supporting member, such as an angle iron 75 (Figures 12, 13 and 17) carried between sections of the cross bar 65 and provided with spacing members 76, by which the guide bars 70 are held in proper alignment 55 while a certain amount of vertical play is provided.

The free ends of the flexible wires 60 are respectively secured to the lower ends of a plurality of levers 80, which are pivoted on a rod 65 61 mounted on the side members 22 by means of yokes 82 and carrying spacing washers 83, by which the levers are properly spaced (Figures 1 and 3). The upper ends of the levers extend through slots 84 in an arcuate index 70 plate 85, which is mounted on brackets 86 supported by the side member 23 of the frame. The ends of the flexible wires 60 located within the grooves 74 of the guide bars 70 are preferably curved into U-shaped form, as illustrated in 75 Figure 12, and secured to the levers 80 at a

point located at the side of the guide bars 70. This causes the wires to seat within the grooves 74 and eliminates any tendency of the wires to bend transversely of said grooves. The guide bars 70 are preferably curved about the rod 81 as a center so that the grooves 74 are properly aligned with the lower ends of the levers 80 throughout the movement of said levers. It is obvious that the guide bars may be utilized with all of the wires 60 if desired, although in the form shown the bars are used to support only the wires which have a comparatively long range of movement. The guide bars are particularly important for the latter wires, inasmuch as the tendency to buckle is greater for wires which extend a greater distance beyond the end of the flexible cables 61.

The type-receiving magazine comprises a plurality of grooved type carriers 90 (Figures 3, 5, 8 and 10), which are similar in form to the type carriers 45 above described. The type carriers 90 are supported by side brackets 91 and 92. The brackets 92 extend upwardly past the type carriers 90 to form ears 93, which are pivoted to links 94, as by pins 95. The links 94 are pivoted, 90 as at 96, to the magazine supports 31.

The brackets 91 are extended downwardly past the type carriers 90 and are pivoted, as by pins 100, to links 101 which are rigidly secured to a shaft 102. The shaft 102 is mounted in 105 suitable bearings in the printing head supports 25, as shown in Figure 1, and carries an operating handle 103.

The brackets 91 are also provided at their lower ends with extensions 104 carrying a ribbon spool support 105 on which a ribbon 106 is adapted to be wound. The support 105 also carries a ratchet 110 cooperating with a pawl 111 to advance the ribbon as the machine is operated. The pawl 111 (Figures 3 and 10) is mounted on a shaft 112, journaled in one of the magazine supports 31 and extending beyond said support to carry a handle 113, by which the pawl may be held out of engagement with the ratchet 110 to permit the ribbon to be rewound. The pawl 111 is held in operating position with respect to the ratchet 110 by means of a spring 114, which may be secured to a stationary stud 115 on the magazine support and may bear against the top surface of said pawl. 110

A pin 116 may be provided to limit the movement of the pawl when it is out of engagement with the ratchet 110.

The ribbon may be carried on a shaft 120 journaled in the printing head supports 25 and extended laterally to carry a handle 121 (Figures 4, 8 and 10), by which the ribbon may be rewound. The ribbon is threaded from the shaft 120 past the shaft 102 and past a supporting member 122, which is carried on the links 101, and thence to the ribbon spool on the support 105.

A frame 124 (Figures 5, 8 and 10) having side members 125 may be slidably mounted on the brackets 91, as by screws 126, carried by said brackets and cooperating with elongated slots 130 formed in the side members 125. The frame 124 carries a plurality of locking bars 131, which are wedge-shape in cross section and are adapted 140 to extend across the various type carriers 90. The top surface of each carrier is recessed to receive said bars and to permit the bars to engage the type pieces. The various type pieces are provided with wedge-shaped grooves 132, 145

- which are adapted to receive the locking bars 131 by which the type pieces are aligned and locked in position. The frame 124 is held in locking position by a spring 133, which is secured between the side pieces 125 and brackets 91. The side pieces 125 also carry pins 134, which are adapted to cooperate with a slot 135 in a pivoted lever 136 (Figure 5) to elevate the frame and to release the locking bars 131 from the type or to positively force the locking bars 131 into engagement with the type and to cause the wedge-shaped surfaces to properly align the same. The forked end of the lever 136 is provided with a shoulder 137, which is adapted to engage the pins 134 and to thereby securely lock the type-receiving magazine 44 against the type-storage magazine 43 when the lever 136 has engaged the pins 134 to hold the frame 124 in elevated position.
- 20 The lever 136 is pivoted, as at 140, in the magazine supports 31 and is extended, as at 141, to engage a link 142 (Figures 3, 4 and 10). The link 142 is pivoted to a lever 143, which extends through a slot 144 in the index plate 85 and is pivoted about the rod 81. A spring 145 may be secured between the lever 143 and a portion of the frame of the machine to normally hold said lever in retracted position, whereby the lever 136 is normally disengaged from the pins 134.
- 25 The upper part of the frame 124 is provided with a cam surface 150 (Figures 8 and 10), which is adapted to engage a cam surface 151 formed of a cross member 152, carried by the links 101 to firmly seat the frame 124 and to thereby bring the locking bars 131 into locking engagement with the grooves 132, formed in the type pieces when the type-receiving magazine 44 is brought into printing position, as illustrated in Figure 10, thereby preventing the printing force from causing the locking bars 131 to unseat and permit the type to move from printing position.
- 30 An aligning member 154 (Figures 10 and 16) is carried by the magazine supports 31 and has a cam surface 155, adapted to engage the lower edge of the stack of type carriers 90 comprising the type-receiving magazine 44, and to thereby direct the type-receiving magazine into correct alignment with the type-storage magazine 43.
- 35 In a machine adapted to print the ticket illustrated in Figure 2, certain of the type, for example the type designating "Quality", "P. G. No.", "Yds.", "Color" and "Order", may be permanently set, whereas the characters referring to the above items may be changed at frequent intervals. The type to be permanently set may be secured in the proper type channels by means of set screws 160 (Figure 9) and the member 154 may be recessed, as at 161 (Figure 16), to provide clearance for the set screws 160. It is to be understood that any desired number of the type may be permanently set by means of these set screws and the remaining type spaces may be adjusted by means of the sliding rows of type above described.
- 40 The index plate 85 may be provided with a plurality of notches 162 adapted to engage lugs (not shown) on the levers 80 to properly align the levers in the various selected positions. The levers 80 may be mounted slightly off-center with respect to the slots 84 so as to resiliently hold said levers in engagement with the notches 162. The guide bars 70 may also be located off-center with respect to the levers 80 for the same purpose. In certain instances, it may be desirable
- 45 to visually designate the setting of the levers 80. For this purpose, the levers may be provided with arcuate plates 164 (Figures 14 and 15) having suitable designations thereon and adapted to register with a slot 165 formed in the index plate 85.
- 50 In the operation of the above-described device, the permanent designations are set in the proper type channels and type pieces are locked therein by means of the set screws 160 (Figure 9). The rows of type are then applied to the remaining channels, preferably in numerical or alphabetical order or, at any rate, in the order designated upon the index plate 85. These type pieces are applied in such relative positions that, when they are locked by the locking bars 131 and the type-receiving magazine 44 is removed from alignment with the type-storage magazine 43, the exposed type faces are in printing position. The receiving magazine consequently provides a type form by which printing is effected.
- 55 In order to set the desired type, the various levers 80 are moved a distance corresponding to the designations desired to be set, thereby causing the pushers 56 to move the various rows of type upwardly from the type-storage magazine into the type-receiving magazine. During this type-setting operation, the lever 143 is operated against the tension of the spring 145 to actuate the lever 136 and to cause the same to elevate 105 the frame 124 carrying the locking bars 131. This permits free movement of the rows of type within the various type channels.
- 60 After the proper type has been set, the lever 143 is released, thereby permitting the locking 110 bars 131 to engage the grooves 132 in the type pieces which are in alignment therewith and to securely lock within the type-receiving magazine the type which has been pushed into said magazine in the setting operation.
- 65 A ticket or the like to be printed is then placed upon the printing bed 32 and the handle 103 is operated to cause pivotal movement of the links 101. The type-receiving magazine 43 thereby pivots about the links 101 and 94 into the printing position illustrated in Figure 10. In this position, the ribbon 106 extends between the type faces and the ticket to be printed. Hence, the pressure of the type faces transfers ink from said ribbon on to said ticket. At the end of 125 the printing operation, the handle 103 is moved in the reverse direction to again swing the type-receiving magazine 43 into alignment with the type-storage magazine 44, the cam surface 155 serving to insure the correct alignment. Thereafter, a second ticket or the like may be printed with the type as previously set up, or certain of the type designations may be changed in order to print, for example, a different order number on the succeeding ticket. To change 130 the type, the lever 143 is moved to release the locking bars, whereupon the proper lever 80 may be moved to its new position and the type relocked. It will be noted that this type-resetting operation is simple and rapid and does not appreciably delay the successive printing operations. Furthermore, the shoulders 137 of the levers 136 engage the pins 134 so as to securely lock the type-receiving magazine against movement while the frame 124 is elevated to release 145 the type for resetting. This prevents the type-receiving magazine from being moved except when the type is securely locked therein.
- 70 The cam surface 151 engaging the surface 150 on the frame 124 securely locks the type at the 150

moment of printing and prevents the printing pressure from deranging the same. This surface also prevents the type-receiving magazine from being brought into printing position unless the type is locked therein.

Although an inking ribbon has been shown for purpose of illustration, it is obvious that other inking means may be employed if desired and also that the ribbon may be automatically wound or rewound by suitable mechanism well known in the art. In the form illustrated, the movement of the type-receiving magazine into alignment with the type-storage magazine after each printing operation causes the ratchet 110 to engage the pawl 111 and to advance the ribbon 106 one step. This mechanism is shown, however, merely by way of illustration and not as a limitation of the present invention.

It will be noted that certain of the slots 84 and certain of the type carriers are shown to be of greater length than others. This, in the form illustrated, is to permit these type carriers to receive the twenty-six letters of the alphabet, whereas the remaining type carriers are adapted to receive the ten figures. It is obvious that the number of carriers to which letters are applied and to which figures are applied may be varied as desired in order to suit any particular case. The guide bars 70 are of importance where the flexible wires extend beyond their supporting cables a substantial distance, inasmuch as a long, unsupported section of the wire would tend to buckle during the type-setting operation. The pivotal support for the guide bars permits them to compensate for any inaccuracies in position with respect to the movement of the levers 80 and thereby prevents them from binding or interfering with the free movement of the levers. It is also to be noted that the type magazines are mounted at a substantial angle to the horizontal. This angle is sufficient to cause the type to slide downwardly into a type-receiving magazine when the pushers 56 are retracted. It is obvious, however, that mechanical means for causing positive return of the type could be employed if desired. It is also obvious that various other means may be employed for releasing the locking bars 131 and that the lever 143 has been shown for this purpose merely as a matter of convenience.

Although one embodiment of the invention has been shown by way of illustration, it is to be understood that the invention is not to be limited thereto but only in accordance with the following claims when interpreted in view of the prior art.

I claim:

1. A printing machine having a pair of aligned stacks of type carriers forming a type-storage magazine and a type-receiving magazine respectively, each type carrier having parallel channels adapted to receive rows of type, means for selectively advancing the rows of type in the various channels from the type-storage magazine into the type-receiving magazine, means for separating the type-receiving magazine from the type-storage magazine to expose the faces of certain type in one of said magazines, and printing means cooperating with the exposed type faces.

2. A printing machine having a pair of aligned stacks of type carriers forming a type-storage magazine and a type-receiving magazine respectively, each type carrier having parallel channels adapted to receive rows of type, means for

selectively advancing the rows of type in the various channels from the type-storage magazine into the type-receiving magazine, means for separating the type-receiving magazine from the type-storage magazine to expose the faces of certain type in one of said magazines, means securing said certain type in said magazine whereby said magazine is adapted to serve as a printing form, and printing means cooperating with the exposed type faces.

3. A printing machine having a pair of aligned stacks of type carriers forming a type-storage magazine and a type-receiving magazine respectively, each type carrier having parallel channels adapted to receive rows of type, rows of type positioned in each channel with the type faces in planes extending transversely of said channels, means for selectively advancing the rows of type in the various channels from the type-storage magazine into the type-receiving magazine, means for separating the type-receiving magazine from the type-storage magazine to expose the faces of certain type in one of said magazines, and printing means cooperating with the exposed type faces.

4. A printing machine having a pair of aligned stacks of type carriers forming a type-storage magazine and a printing form respectively, each type carrier having parallel channels adapted to receive rows of type, rows of type positioned in each channel with the type faces in planes extending transversely of said channels, and means for selectively advancing the rows of type in the various channels from the type-storage magazine into the printing form to bring the faces of certain type into operative position between said stacks whereby said certain type is adapted to be utilized for printing.

5. A printing machine having a pair of aligned stacks of type carriers forming a type-storage magazine and a type-receiving magazine respectively, each type carrier having parallel channels adapted to receive rows of type, rows of type positioned in each channel with the type faces in planes extending transversely of said channels, means for selectively advancing the rows of type in the various channels from the type-storage magazine into the type-receiving magazine to bring the faces of certain type into operative position between said magazines, and printing means adapted to cooperate with the exposed type faces.

6. A printing machine having a pair of aligned stacks of type carriers forming a type-storage magazine and a type-receiving magazine respectively, each type carrier having parallel channels adapted to receive rows of type, rows of type in each channel of said type-storage magazine with the type faces extending away from the type-receiving magazine, means for selectively advancing the rows of type in the various channels from the type-storage magazine into the type-receiving magazine, means for removing the type-receiving magazine from alignment with the type-storage magazine whereby the faces of certain type in said type-receiving magazine are exposed for printing, and printing means cooperating with the exposed type faces.

7. A printing machine having a pair of aligned stacks of type carriers forming a type-storage magazine and a type-receiving magazine respectively, each type carrier having parallel channels adapted to receive rows of type, rows of type in each channel of said type-storage magazine with the type faces extending away from

- the type-receiving magazine, means for selectively advancing the rows of type in the various channels from the type-storage magazine into the type-receiving magazine, means for securing 5 the type in said type-receiving magazine, means for removing the type-receiving magazine from alignment with the type-storage magazine whereby the faces of certain type in said type-receiving magazine are exposed for printing, and 10 printing means cooperating with the exposed type faces.
8. In a printing machine, a stack of type carriers having channels adapted to receive rows of type, type pieces arranged end-to-end in said 15 channels with the printing face of one type piece against the base of the next type piece, and means for selectively advancing the rows of type in said channels whereby selected type faces are brought into printing position.
9. In a printing machine, a type carrier having a plurality of parallel channels adapted to receive type, a plurality of rows of type in said channels, each of said rows comprising type pieces positioned end-to-end with their printing 20 faces in parallel planes, means for selectively advancing said rows in said channels to bring the desired type faces into printing position, and means to lock the type pieces in printing position.
10. In a printing machine, a type carrier having a plurality of parallel channels adapted to receive type, a plurality of rows of type in said channels, each of said rows comprising type pieces positioned end-to-end with their printing 25 faces in parallel planes, means for selectively advancing said rows in said channels to bring the desired type faces into printing position, and means to lock the type pieces in printing position comprising a transverse bar adapted 30 to engage a depression in said type pieces.
11. In a printing machine, a type carrier having a plurality of parallel channels adapted to receive type, a plurality of rows of type in said channels, each of said rows comprising type pieces positioned end-to-end with their printing 35 faces in parallel planes, means for selectively advancing said rows in said channels to bring the desired type faces into printing position, and means to lock the type pieces in printing position comprising a transverse bar extending across said carrier and adapted to engage 40 depressions in the type pieces.
12. In a printing machine, a type carrier having a plurality of parallel channels adapted to receive type, a plurality of rows of type in said channels, each of said rows comprising type pieces positioned end-to-end with their printing 45 faces in parallel planes, means for selectively advancing said rows in said channels to bring the desired type faces into printing position, and means to lock the type pieces in printing position comprising a transverse member having a wedge-shaped cross section and extending across said type carrier, each type piece having a 50 wedge-shaped groove adapted to engage said transverse member to align said type pieces and to hold the same in position.
13. In a printing machine, a stack of type carriers having channels adapted to receive rows of type, type pieces arranged end-to-end in said channels with the printing face of one type piece against the base of the next type piece, and means for selectively advancing the rows of type 55 in said channels whereby selected type faces are brought into printing position, and means to align the various type faces for printing.
14. In a printing machine, a stack of type carriers having channels adapted to receive rows of type, type pieces arranged end-to-end in said channels with the printing face of one type piece against the base of the next type piece, means for selectively advancing the rows of type in said channels whereby selected type faces are brought into printing position, and means to secure said type in printing position in said carriers whereby said stack is adapted to constitute a printing form.
15. In a printing machine, a stack of type carriers having channels adapted to receive rows of type, type pieces arranged end-to-end in said channels with the printing face of one type piece against the base of the next type piece, means for selectively advancing the rows of type in said channels whereby selected type faces are brought into printing position, and a transverse bar extending across each of said carriers, said type pieces having grooves adapted to engage said bar to lock said type in position.
16. In a printing machine, a stack of type carriers having channels adapted to receive rows of type, type pieces arranged end-to-end in said channels with the printing face of one type piece against the base of the next type piece, means for selectively advancing the rows of type in said channels whereby selected type faces are brought into printing position, a transverse bar extending across each of said carriers, said type pieces having grooves adapted to engage said bar to lock said type in position, a frame carrying said bars, and means normally holding said frame in locking position.
17. In a printing machine, a stack of type carriers having channels adapted to receive rows of type, type pieces arranged end-to-end in said channels with the printing face of one type piece against the base of the next type piece, means for selectively advancing the rows of type in said channels whereby selected type faces are brought into printing position, a transverse bar extending across each of said carriers, said type pieces having grooves adapted to engage said bars to lock said type in position, a frame carrying said bars, means normally holding said frame in locking position, and a releasing lever adapted to actuate said frame for releasing or locking the type.
18. In a printing machine, a pair of stacks of type carriers forming type magazines having aligned channels adapted to receive rows of type, means for selectively advancing the type in said rows to position desired printing faces between said magazines, means to lock the type in said selected position, and means operable when said magazines are aligned for releasing said locking means, said releasing means being adapted to prevent separation of said magazines when said locking means is released.
19. In a printing machine, a type carrier having a plurality of parallel type channels, type pieces permanently secured in printing position in certain of said channels, and rows of separate type pieces slidably carried end-to-end in others of said channels and adapted to be selectively advanced into printing position.
20. In a printing machine, a frame, a stack of type carriers supported thereby, each carrier having a plurality of channels adapted to receive rows of type in end-to-end relationship, a type-receiving magazine comprising similar car-

- riers registering with said first carriers, type-locking means associated with said magazine, and a lever mounted on said frame and adapted to engage said locking means when said first and second carriers are in register. 5
21. In a printing machine, a frame, a stack of type carriers supported thereby, each carrier having a plurality of channels adapted to receive rows of type in end-to-end relationship, a type-receiving magazine comprising similar carriers registering with said first carriers, type-locking means associated with said magazine, a lever mounted on said frame and adapted to engage said locking means when said first and second carriers are in register, and manual means to operate said lever. 10
22. In a printing machine, a stack of type carriers having channels to receive rows of type, type-locking means associated with each carrier, a frame carrying all of said locking means, a pin on said frame, and a forked lever adapted to engage said pin for controlling said locking means. 15
23. In a printing machine, a stack of type carriers having channels to receive rows of type, type-locking means associated with each carrier, a frame carrying all of said locking means, a pin on said frame, and a forked lever adapted to engage said pin for releasing said locking means, said forked lever having means to prevent movement of said type carriers while said locking means is in released position. 20
24. A printing machine comprising a type-storage magazine having channels adapted to carry rows of type, a type-receiving magazine adapted to constitute a printing form and having channels registering with said first channels, and means for selectively advancing the rows of type into said type-receiving magazine to bring the desired type into printing position therein. 25
25. A printing machine comprising a type-storage magazine having channels adapted to carry rows of type, type pieces arranged end-to-end in said channels with their printing faces extending in parallel planes transverse to said channels, a type-receiving means adapted to constitute a printing form and having channels registering with said first channels, and means for selectively advancing the rows of type through the printing position in said type-receiving means to bring the desired type into printing position therein. 30
26. A printing machine comprising a type magazine having a plurality of type-receiving channels, a row of type in each channel, a pusher in each channel adapted to selectively advance the type of each row, a lever adapted to selectively position said type, and mechanical means including a flexible wire and cable interconnecting said pusher and said lever. 35
27. A printing machine comprising a set of type carriers, rows of type in said carriers, means to selectively advance the type of each row to bring selected type faces into printing position comprising pushers cooperating with each row of type, and a lever adapted to progressively operate each of said pushers. 40
28. A printing machine comprising a set of type carriers, rows of type in said carriers, means to selectively advance the type of each row to bring selected type faces into printing position comprising pushers cooperating with each row of type, a lever adapted to progressively operate each of said pushers, and an index plate associated with said levers, said index plate having positioning means adapted to position said levers for selecting the desired type. 45
29. In a printing machine, a printing bed, a type form comprising a type carrier having channels corresponding to the different type spaces, means to advance a row of type into each of said channels to bring selected type faces of each row into printing position in said form, and means to shift said form with said rows of type into printing relationship with said printing bed. 50
30. In a printing machine, a type-storage magazine having parallel type channels, a type-receiving magazine having channels adapted to register with said first channels, means to selectively advance type in said channels, a printing bed, means to shift said type-receiving magazine into printing relationship with said bed and into alignment with said type-storage magazine, and a guide member having a cam surface adapted to guide said type-receiving magazine into correct alignment with said type-storage magazine. 55
31. In a printing machine, a pair of stacks of type carriers having type-receiving channels in aligned position, type pieces located in rows end-to-end in said channels, said channels extending at an angle to the horizontal whereby said type pieces tend to fall to the lower end of each channel, pusher means located in said channel and adapted to selectively elevate said type rows therein, and means to selectively operate said pusher means. 60
32. In a printing machine, a printing bed, a type form comprising a type carrier having channels corresponding to the different type spaces, means to advance rows of type into said channels to bring selected type faces into printing position in said form, means to shift said form into printing relationship with said printing bed, means to lock said type in said form, and means to prevent movement of said form into printing position unless said type has been locked. 65
33. In a printing machine, a printing bed, a type form comprising a type carrier having channels corresponding to the different type spaces, means to advance rows of type into said channels to bring selected type faces into printing position in said form, means to shift said form into printing relationship with said printing bed, and means operable upon movement of said form into printing position to lock the type therein. 70
34. In a printing machine, a stack of type carriers adapted to constitute a printing form, locking means to lock type in said carriers, a frame carrying said locking means, said frame having a cam surface, and means engaging said cam surface when said stack is moved into printing position to thereby render said locking means operative. 75
35. In a printing machine, a plurality of type carriers having channels adapted to carry rows of type, pusher means to selectively advance said type, a lever adapted to control said pusher means, and a flexible wire and cable mechanically interconnecting said lever and said pusher means, the end of said wire adjacent said lever being seated in an arcuate, grooved guide bar. 80
36. In a printing machine, a plurality of type carriers having channels adapted to carry rows of type, pusher means to selectively advance said type, a lever adapted to control said pusher 85

- means, and a flexible wire and cable mechanically interconnecting said lever and said pusher means, the end of said wire adjacent said lever being seated in an arcuate, grooved guide bar, 5 said guide bar being pivoted at one end and being constrained for limited movement about said pivot to compensate for inaccuracies in alignment with said lever.
37. A printing machine comprising a set of 10 type carriers, rows of type in said carriers, means to selectively advance the type of each row to bring selected type faces into printing position comprising pushers cooperating with each row of type, a lever adapted to progressively operate 15 each of said pushers, and an index plate associated with said levers, said index plate having positioning means adapted to position said levers for selecting the desired type and means to resiliently hold said levers in engagement with 20 said positioning means.
38. In a printing machine, a type-storage magazine, a printing form registering with said magazine and adapted to receive type therefrom, a printing bed, means to move said printing form 25 into printing engagement with said bed, and an inking ribbon normally carried in inoperative position and movable with said printing form into position between said form and the printing bed.
39. In a printing machine, a type-storage magazine, a printing form registering with said magazine and adapted to receive type therefrom, a printing bed, means to move said printing form 30 into printing engagement with said bed, an inking ribbon normally carried in inoperative position and movable with said printing form into position between said form and the printing bed, and means to advance said ribbon at each printing operation.
40. In a printing machine, a type-storage magazine, a printing form registering with said magazine and adapted to receive type therefrom, a printing bed, means to move said printing form 35

- into printing engagement with said bed, an inking ribbon normally carried in inoperative position and movable with said printing form into position between said form and the printing bed, and means including a pawl and ratchet associated with said printing form to advance said ribbon at each printing operation.
41. In a printing machine, a type-storage magazine, a printing form registering therewith, means to advance type end-to-end from said storage magazine into said form, means to lock the selected type in said form, and means to linearly separate said form from said magazine and to cause pivotal movement of said form to bring the same into printing position.
42. In a printing machine, a stack of type carriers having channels adapted to receive rows of type, a printing form having channels registering with said first channels and adapted to receive the rows of type which are moved longitudinally of said first channels, one type face of each row being in printing position in said form.
43. In a printing machine, a stack of type carriers, each carrier having a plurality of type channels corresponding to a line of printing, and a printing form having channels registering with said first channels and adapted to receive type therefrom with the type faces exposed for printing, whereby a plurality of lines may be set and printed as a unit.
44. In a printing machine, a stack of type carriers, each carrier having a plurality of type channels corresponding to a line of printing, a printing form having channels registering with said first channels and adapted to receive type therefrom with the type faces exposed for printing, whereby a plurality of lines may be set and printed as a unit, and means to move said printing form from registration with said carriers into printing position.
